PORTABLE TUFTING MACHINE

Theron F. Gifford, Lookout Mountain, Ga., assignor to Ten-Tex Corporation, Chattanooga, Tenn., a corporation of Tennessee

Application November 6, 1953, Serial No. 390,659

8 Claims. (Cl. 112—80)

This invention relates to tufting machines, and more specifically to a portable type tufting machine.

It is an object of this invention to provide a tufting device having a novel and effective means for advancing the machine along the surface of the work.

Still another object is the provision in a tufting machine of means for adjustably varying the distance between stitches.

A further object is to provide a tufting machine having a yarn feed mechanism wherein the yarn is fed through only a portion of the sewing cycle of the needle.

Still a further object is to provide a tufting machine having means for varying the length of the needle stroke.

Further objects and many advantages will become apparent to those skilled in the art from a reading of the following detailed description of a physical embodiment of the invention, in conjunction with the accompanying drawings, wherein—

Figure 1 is a side elevation view taken in partial section along line 1—1 of Figure 2.

Figure 2 is a plan view taken in partial section along line 2—2 of Figure 1.

Figure 3 is an end view of the embodiment as viewed from the needle end.

Figure 4 is a side view of a part of the device showing the yarn feeding mechanism.

Figure 5 is a partial section view taken along line 5—5 of Figure 2.

Referring in detail to the drawings, a housing, generally designated 11, having a portion thereof formed as a handle 12, has mounted transversely therein in bearing 13 a drive shaft 14. Suitably secured to shaft 14, as with a set screw 15, is a bevel gear 16 which meshes with a complementary bevel gear 17 secured to a coupling shaft 18. Shaft 18 is mounted for rotation in a bearing 19 and extends outside the housing 11 for connection, as through a flexible shaft, to any suitable external power drive source. The handle 12 may enclose a suitable switch mechanism 21 which may be actuated by a trigger 22 for controlling the drive motor or other power source (not shown).

One end 31 of the housing 11 is shaped similarly to a pistol barrel and has fixedly secured therein a sleeve 32 which has a slot 33 formed in one side thereof. Reciprocably mounted in sleeve 32 is a needle slide 34, in the outer end of which is suitably held a hollow or other suitable type needle 35. The needle slide 34 and needle 35 are reciprocated by a connecting rod 36 pivotally connected to the inner end of slide 34.

The connecting rod 36 is adjustably and pivotally fastened by means of sleeve 41, bolt 42, and nut 43, to a pair of crank arms 44 and 45, in which are formed radial slots 46 and 47, respectively, and which are fixed to drive shaft 14 and stub shaft 48, respectively. Crank arm 44 has a counterweight 49 in order to minimize vibrations. By adjusting the connecting bolt 42 to vari-

2

ous radial positions in the slots 46, 47 the length of the stroke of the needle 35 may be adjusted as desired.

It is an important feature of my invention that means are provided, as next described, for adjusting the distance between stitches. In the illustrated embodiment this takes the form of a pair of wheels 51 having spikes or needles 52 extending radially from their peripheral surfaces, and being mounted for rotation in a bracket 53 suitably secured onto the outer end of sleeve 32. 10 Connected through a unidirectional clutch 54 to one of the wheels 51 is a lever arm 55 which has a slot 56 therein. Obviously, other suitable unidirectional clutch devices, such as a ratchet and pawl arrangement, may be used in lieu of the illustrated clutch 54 (see Fig. 5) if desired. Adjustably and pivotally connected at a desired point in the slot 56 by means of bolt 57, spacer sleeve 58, and nut 59, is a connecting rod 61. Connecting rod 61 is pivotally connected at its other end to a cam follower bar 62. Bar 62 has a roller 63 mounted in its inner end and is spring-urged, as indicated at 64, for constant engagement of roller 63 with cam 65. Cam 65, which is fixedly mounted on shaft 14, has an abrupt raised portion 66 which during each rotation thereof causes the bar 62 to be reciprocated out and in one time. 20 This reciprocatory motion is translated through connecting rod 61, lever arm 55, and unidirectional clutch 54 into an angular step-by-step rotation of wheels 51, which in turn are in contact with the fabric and thereby advance the needle 35 and end of sleeve 32 along the fabric for the next stroke of the needle. It will be apparent that the cam 65 is so positioned angularly on shaft 14 that this movement of the wheels 51 takes place during the period when the needle 35 is retracted within the sleeve 32. By adjusting the connecting point of connecting rod 61 in the slot 56 of lever arm 55 it will be seen that the step-by-step angular amount of rotation of wheels 51, and thus the distance between stitches may be conveniently and easily varied over a fairly wide range.

40 As seen in Figures 2—4, there is provided a pair of feed rollers 71, 72 for periodically feeding yarn to the needle 35. Feed roller 71 is fixedly mounted on stub shaft 48 for rotation therewith, and has a knurled surface 73 (see Figure 3) over a portion of its circumferential periphery. 45 The remaining portion 74 of the periphery of roller 71 is reduced in radius, as best seen in Figure 4. The roller 72 is mounted for free rotation on a lever 75 pivotally mounted as indicated at 76 on the side of removable side plate 77 of the housing 11. Feed roller 72 has a circumferential channel groove 78 formed therein for engagement with the knurled outer periphery of feed roller 71, and is spring-urged into engagement therewith by spring 79 which biases arm 75 in a clockwise direction as viewed in Figure 4. A stop pin 80 fixed in the side plate 50 77 limits downward movement of arm 75 such that channel groove 78 engages only the knurled portion 73 of feed roller 71 and makes no engagement with the reduced peripheral portion 74.

55 Thus, it will be seen that yarn, which is passed from a suitable supply (not shown) through eyelet 81, between feed rollers 71, 72, through guide opening 82, and thence down through sleeve 32 to the needle 35, will be fed by rollers 71, 72 periodically once during every cycle of the sewing operation. Preferably, as shown in the illustrated construction, this feeding of the yarn takes place during the downstroke of the needle 35, while no yarn is fed during the upstroke of the needle.

60 In operation, the operator grasps the machine by the handle 12 and holds it with the end of sleeve 32 and the wheels 51 in engagement with the fabric to be worked upon. He then presses the trigger 22, actuating switch 70 21 to start the motor (not shown) which drives the mecha-

nism through connecting shaft 18. The needle 35 is thereby reciprocated through the rotation of shaft 14 and the consequent rotary to reciprocating action of crank arms 44, 45, connecting rod 36 and the needle slide 34. During each stroke of the needle 35, yarn is periodically fed thereto through the action of feed rollers 71 and 72, roller 71 being driven by rotation of stub shaft 48. At or near the top of each upstroke of the needle 35, the sleeve 32 is moved forward a predetermined distance through the small angular movement of the wheels 51, which are spiked to positively engage the fabric and assure a definite amount of movement. Movement of wheels 51 is accomplished through the action of cam 65 mounted on shaft 14, cam follower 62, connecting rod 61, lever arm 55, and unidirectional clutch 54. By adjusting the radial connecting position of connecting rod 36 in the radial grooves 46, 47 in crank arms 44, 45 the length of stroke of the needle 35 may be varied, as desired. Similarly, the distance between stitches may be varied by adjusting the connection point of connecting rod 61 to various radial positions along the slot 56 of lever arm 55.

It will be apparent from the foregoing that with the instant invention repairs may readily be made in defective tufted articles, or entirely new tufted articles may be made with this machine. In the use of the present machine constructed in accordance with my invention, the stroke of the needle may easily be adjusted as may the length of the stitch. Thus the machine is easily adaptable to varying conditions and requirements in the making of tufted articles.

Obviously, many modifications of my invention will be readily apparent from a reading of this specification without departing from the scope or spirit of the invention. It is to be understood, therefore, that the construction shown is only that of a preferred embodiment and that my invention is not to be construed as limited thereto except as defined by the appended claims.

What is claimed is:

1. A tufting machine of a type which is bodily carried in the hand and guided by the hand relative to the work during use, said machine comprising a body portion, reciprocatory needle means carried by said body portion, step-by-step feed means carried by the body portion and operable to advance the body portion and needle means relative to the work, reciprocatory means connected with said step-by-step feed means to actuate the same each time the needle means is near the top of its upstroke, intermittent positive yarn feed means carried by the body portion and adapted to feed yarn to the needle means during the downstroke of the needle means, and a single rotary driving means for said needle means, second-named reciprocatory means and yarn feed means carried by said body portion.

2. A tufting machine of a type which is bodily carried in the hand and guided by the hand relative to the work during use, said machine comprising a body portion, reciprocatory needle means carried by the body portion, step-by-step rotary feed means carried by the body portion and operable to advance the body portion and needle means relative to the work when the needle means is near the top of its upstroke, second reciprocatory means connected with said rotary feed means to actuate the same when the needle is near the top of its upstroke, rotary frictional positive yarn feed means carried by the body portion and adapted to feed yarn to the needle means during the downstroke of the latter, and a common rotary driving means for and connected with said needle means, second reciprocatory means and yarn feed means and adapted to operate such means in properly timed relation.

3. A hand carried and hand guided portable tufting implement comprising a body portion shaped so as to be conveniently held in the hand, reciprocatory needle means carried by the body portion, intermittently operated rotary feed means carried by the body portion for advancing the body portion and needle means step-by-step

over the work, second reciprocatory means carried by the body portion and connected with the rotary feed means to operate the same only when the needle is near the end of its upstroke, positive rotary yarn feed means carried by the body portion and adapted to feed yarn to the needle, a common rotary drive shaft connected with said needle means, second reciprocatory means and yarn feed means to operate the same in timed relation, and means carried by said body portion for driving the rotary drive shaft and adapted for connection with a remote source of rotary power.

4. A hand carried and hand guided portable tufting machine comprising a body portion, a single crank shaft journaled upon the body portion for rotation, means for turning the crank shaft, reciprocatory needle means carried by the body portion and connected with the crank shaft and actuated thereby, intermittently operated step-by-step feed means carried by the body portion and operable to advance the body portion and needle means relative to the work when the needle means is near the end of its upstroke, a cam mounted upon the crank shaft and contacting said feed means to operate the same in the desired timed relation to said needle means, an intermittent positive acting yarn feed means mounted upon the body portion and connected with and actuated by said crank shaft and adapted to positively feed yarn to the needle means during the downstroke of the latter.

5. A hand carried and hand guided portable tufting machine comprising a body portion, a crank shaft journaled upon the body portion for rotation and driven from a remote source of power, reciprocatory needle means carried by the body portion and connected with the crank shaft and driven thereby, an intermittently operated rotary element carried by the body portion and engaging the work to advance the machine over the work when the needle is near the end of its upstroke, one way clutch means connected with said rotary element to intermittently turn it, reciprocatory means connected with the body portion and with said clutch means to actuate the latter, a cam having a high point mounted upon the crank shaft to turn therewith and contacting the last-named reciprocatory means to actuate the same each time the needle means is near the top of its upstroke, and positive yarn feed means carried by the body portion and connected with the crank shaft and actuated thereby and adapted to feed yarn to the needle means.

6. A hand carried and hand guided portable tufting machine comprising a body portion, a crank shaft journaled upon the body portion for rotation, means to turn the crank shaft, reciprocatory needle means carried by the body portion and connected with the crank shaft and operated thereby, cloth engaging wheel means journaled upon the body portion for intermittent operation to advance the tufting machine relative to the work each time the needle means is near the top of its upstroke, a one-way clutch device including a slotted arm connected with the wheel means to turn the latter in a step-by-step manner, a reciprocatory element carried by the body portion, a connecting link having one end pivoted to the reciprocatory element and its other end adjustably mounted within the slot of said slotted arm, whereby the amount of rotation imparted by the one way clutch device to said wheel means may be varied, a cam having a high part secured to said crank shaft to turn therewith and contacting the reciprocatory element to actuate the same in properly timed relation to said needle means, and positive yarn feed means carried by the body portion and connected with the crank shaft and operated thereby and adapted to feed yarn to said needle means.

7. A hand carried and hand guided portable tufting implement comprising a body portion, a common rotary means journaled upon the body portion, reciprocatory needle means carried by the body portion and connected with and operated by the common rotary means, intermittent work engaging implement feed means mounted

upon the body portion and connected with and operated by the common rotary means and adapted to advance the implement relative to the work each time the needle means is near the end of its upstroke, a first rotary friction yarn feed element connected with and driven by said common rotary means, and a second rotary friction yarn feed element carried by said body portion and yieldingly contacting the first yarn feed element and coacting therewith during rotation of the first yarn feed element to feed yarn to the needle means during the downstroke of the needle means.

8. A hand carried and hand guided portable tufting machine comprising a body portion, a common rotary means journaled upon the body portion, a reciprocatory needle unit carried by the body portion and connected with and operated by the common rotary means, intermittent work engaging machine feed means mounted upon the body portion and connected with and operated by the common rotary means to advance the machine over the work each time the needle is near the end of its upstroke, a first yarn feed roller having an elevated roughened peripheral portion connected with and driven by said common rotary means, a coacting yarn feed roller, an arm carrying the coacting roller and pivoted to the body portion, and a spring connected with said arm and

10

5

serving to yieldingly urge said coacting roller into peripheral contact with said first feed roller, whereby rotation of the first feed roller with the elevated roughened peripheral portion causes yarn gripped between the first and coacting rollers to be intermittently positively fed to the needle during the downstroke of the latter, the common rotary means driving the needle unit, machine feed means and first yarn feed roller in properly timed relation.
